CLAIM

The ornamental design for a cap with nozzle, as shown and described.

DESCRIPTION

FIG. 1 is a front elevation view the new design;

FIG. 2 is a side elevation view thereof;

FIG. 3 is a rear elevation view thereof;

FIG. 4 is a top plan view thereof;

FIG. 5 is a side elevation view thereof opposite from FIG. 2;

FIG. 6 is a top and side perspective view thereof; and,

FIG. 7 is an exploded view thereof.

The broken lines showing portions of the nozzle serve the purpose of illustrative example and form no part of the claimed design.
